GARMENT HANGER ACCESSORY AND
HANGERWilliam R. Kohl, Glenview, Ill., and William W.
McFall, Mankato, Minn.

Application May 5, 1941, Serial No. 391,846

3 Claims. (Cl. 223—88)

Our invention is a demountable device for im-
position on a garment hanger to lockingly sup-
port accessory articles thereon.

In a process of garment cleaning a constant
and very expensive trouble arises among cleaners
in the loss of articles accessory to garments being
cleaned, and especially is this the case in a large
proportion of women's garments going through
the cleaning process, as each article is sepa-
rately handled in the work. Each article is hung
upon a hanger and these hung garments are
passed along in quantity to a point where a de-
vice of some kind is used to place said garment
in a protecting bag. In an ordinary garment
which is a unit in itself, the ordinary type of
hanger may be used, but where accessories have
to be carefully taken care of the application
herein provides for a specific device which is in-
stantly convenient for locking an accessory to
the hanger and which said hanger is constructed
to take this accessory in the simplest manner and
provide for safety, economy and speed. In many
cleaners' establishments an expense for insur-
ance arises because of the losses encountered by
reason of the accessory getting separated from
the garment to which it belongs. Such a gar-
ment hanger with such an accessory provides
that the accessory can be changed from one
hanger to another to meet the needs of each
individual garment.

In the accompanying drawing is shown an em-
bodiment of our invention in which

Fig. 1 is a garment accessory locking device.

Fig. 2 is a specialized form of a garment hanger
with the garment accessory device thereon.

Fig. 3 is a side view of Fig. 2.

Fig. 4 is an enlarged broken section along the
arrows 4—4.

As illustrated 1—with the arrow—indicates the
general demountable device in which 2 and 3
are parallel bars in a common plane. These bars
are formed into a unitary device by end portions
4 and 4' so formed that the ends 4' form a means
of straddling the device at the junction of the
inclined portions of the triangle and the ver-
tical walls of the rectangle. 4 are curved por-
tions bent inwardly from 4' to the shorter hori-
zontal bar 3; the device is demountably placed
over the hook of a hanger and dropped into
position on the inclined surfaces: the longer
horizontal bar extending adjacent one side of
the hanger and the shorter bar extending for-
ward from the opposite side of the hanger.

This device provides for the locking of a gar-
ment accessory upon a hanger after a garment

has been installed upon the triangular portions
of the hanger. As shown in Fig. 4 when an ac-
cessory, such as a belt or necklace, is hung on 2
and the folds brought over 3 the garment nor-
mally locks itself by friction with the locking
device.

In Fig. 2 we show a hanger consisting of a hook
of the ordinary type with a shank supporting a
form with three sides, the base portion being
open, and the same forming a portion of a de-
pendent triangle 5 consisting of inclined por-
tions 14 and 15 and a horizontal base 9. This
type of hanger is peculiarly adapted to the gen-
eral garment cleaning business. In the han-
dling of garments and placing the same upon the
hangers the formation in Fig. 2 provides a hand
hold in handling quantities of garments; where
the hook is inefficient.

In Fig. 5 we show the accessory mounted on
a standard type of wire hanger, which is the
type most commonly used by garment cleaners.

A—in dotted lines—refers to a type of acces-
sory as applied to the specific garment accessory
locking device.

We claim:

1. In combination, a garment hanger having a
triangular body portion and a hook member at
the apex of said body portion, an auxiliary de-
mountable garment supporter comprising two
spaced bars connected at adjacent ends to form
an elongated flattened loop member, the apex
of the hanger passing through said loop mem-
ber, the spacing of the bars at the ends of the
said loop member being only slightly greater
than the thickness of the body portion of the
garment hanger.

2. In combination, a wire garment hanger
having a generally triangular body portion and
a hook member at the apex of said body portion,
said hook member being connected with the tri-
angular body portion at the apex of the body
portion by a neck centering portion comprising
two upstanding bars which are spaced substan-
tially from each other at opposite sides of the
hook portion, an auxiliary demountable garment
supporter comprising two spaced bars connected
at adjacent ends to form an elongated flattened
loop member of substantially the same length as
the spacing of the bars forming the neck cen-
tering portion, the apex of the hanger passing
through said loop member with the bars of the
neck centering portion disposed within the ends
of said loop member, the spacing of the bars of
the garment supporter at the ends of said loop
member being only slightly greater than the

thickness of the body portion of the garment hanger.

3. In combination, a wire garment hanger having a generally triangular body portion and a hook member at the apex of said body portion, said hook member being connected with the triangular body portion at the apex of the body portion by a neck centering portion comprising two upstanding bars which are spaced substantially from each other at opposite sides of the hook portion, an auxiliary demountable garment supporter comprising two spaced bars connected at adjacent ends to form an elongated flattened loop member of substantially the same length

as the spacing of the bars forming the neck centering portion, the apex of the hanger passing through said loop member with the bars of the neck centering portion disposed within the ends of said loop member, the spacing of the bars of the garment supporter at the ends of said loop member being only slightly greater than the thickness of the body portion of the garment hanger, and the spacing of said bars intermediate the ends of the loop member being considerably greater than the thickness of the body portion of the garment hanger.
